UNITED STATES PATENT OFFICE

172,959

VALET STAND OR SIMILAR ARTICLE

Ruth Brooks Flippen, Tarzana, Calif.

Application February 15, 1954, Serial No. 29,014

Term of patent 14 years

(Cl. D33—8)

To all whom it may concern:

Be it known that I, Ruth Brooks Flippen, a citizen of the United States, residing at Tarzana, in the county of Los Angeles, and State of California, have invented a new, original, and ornamental Design for a Valet Stand or similar article, of which the following is a specification, reference being had to the accompanying drawing, forming part thereof, in which:

Fig. 1 is an isometric view of a valet stand or similar article, showing my new design; and

Fig. 2 is a side view thereof.

I claim:

The ornamental design for a valet stand or similar article, substantially as shown.
